EMBROIDERING MACHINE

Max Bretschneider, Plauen, Germany

Application October 20, 1930, Serial No. 490,027
In Germany October 24, 1929

10 Claims. (Cl. 112—86)

The present invention relates to embroidering machines of the multiple needle type, in which the fabric to be embroidered is held by a vertically and horizontally adjustable frame and the needles are moved to and fro horizontally, and has for its object to provide improvements which considerably increase the working speed of such machines.

For this purpose the frame is supported in a novel manner by suspending its struts and side parts horizontally displaceably from an auxiliary bar held by carrying means, such as steel bands and the like, which can be vertically adjusted by the automatic device. By suspending it in this way the frame is prevented from oscillating in response to the intermittently acting adjusting forces and from interfering with the work of the needles. The new suspension completely excludes bending strains of the longitudinal carriers of the frame, which need not be rigid any more.

In connection with the new frame suspension other improvements are provided in order to utilize the great working speed of embroidering machines to its fullest extent. To insure good balancing of weights and masses, two frames of the kind characterized are arranged on both sides of the supporting machine frame in such a way that one of them always moves oppositely to the other in vertical direction and both are always moved uniformly in horizontal direction, the needle driving rods being disposed on the outer sides of the machine and the shuttles between the two frames so that all mass forces relative to the horizontally reciprocating motions of the embroidering tools balance each other and are thus kept away from the machine frame. In order to transmit reliably the horizontal adjusting forces to all parts of the frame, the side portions of the latter are guided vertically adjustably by two members which, by means of steel bands, can be adjusted according to pattern and drawn apart to keep the frame tensioned so that greater accelerating forces cannot cause harmful vibrations of the frame parts and displace thereby the fabric to be embroidered. The adjustment of the two frames of an embroidering machine by means of steel bands guided over circular discs makes it possible to transmit adjusting motion so as to exclude oscillation. Furthermore, the frame can be adjusted very accurately by disposing the changing shaft with the adjusting wheels inside the embroidering machine.

It is further necessary to provide means for

separating the needles individually from their driving device during high speed operation and stopping them if a thread is broken to thread the yarn again. According to the invention, the needles are therefore secured to needle bars which are individually removably connected with the rod serving as driving means and which are fixedly positioned on the machine frame.

In this way the repeat can be changed easily by disengaging the needles that are not wanted or by reconnecting needles that were previously disengaged with the driving rod. Moreover, in fancy embroidery work differently colored threads may be inserted in the needles in a certain order to work only needles with threads of the same color and to replace them by others with differently colored threads after finishing the particular portion of the work. As the needles can be separated from the driving rod even during high speed operation, the masses to be disengaged are reduced to a minimum and shocks otherwise unavoidable during starting and stopping eliminated.

The drive of the other embroidering tools, and particularly of the bore tools, presser tools, thread guides, as well as the braking device must be adapted to the speed of the needles, it being especially necessary to prevent the presser tools from striking the fabric at full speed as is now the case and to cause them to move intermittently by being first placed softly on the fabric, stopped for a moment, and then tensioned by being exposed to the action of springs which press them against the fabric. In this manner the otherwise unavoidable noise and the excessive stressing of the fabric owing to the impact of the presser tools are eliminated and perfect operation of the machine becomes possible.

One embodiment of the invention is illustrated in the accompanying drawings, in which Figure 1 is a front view of a part of the embroidering machine and of the frame suspension in particular; Fig. 2, a supplementary view to Fig. 1 showing the other part of the embroidering machine; Fig. 3, a vertical section of the embroidering machine; Fig. 4, an end view of the machine frame with the gear required for the lateral adjustment of the frame; Fig. 5 is a fragmentary side view showing the band suspension for the carrier members; Fig. 6, an end view of a portion of Fig. 5; Fig. 7, a top view partly in section showing two carrier members connected together; Figs. 8 and 9, detail views of modifications of the frame support; Fig. 10 is a side view of the embroidering tools in their relative position to one

another; Fig. 11, a side view of the needle drive; Fig. 12, a ground plan of the auxiliary shaft drive; Fig. 13, a ground plan of the needle driving rod; Fig. 14, a view of the control slide in disengaging position; Figs. 15 to 17 are explanatory ground plans of the needle drive, Fig. 15 showing it in drawn back position, Fig. 16, in advanced position, and Fig. 17 after separation from the driving rod; Fig. 18 is a section of the coupling parts on the line A—A, Fig. 17; Fig. 19, a side view of the bore tool drive after disengagement; Fig. 20, a side view of the bore tool drive after engagement; Fig. 21, a ground plan of the guiding parts for the joint of the toggle for the bore tool drive; Fig. 22, a view of the cam for adjusting the guide path for the toggle joint of the bore tool drive; Figs. 23 to 25 are detail views of the presser member with its drive in various positions; Fig. 26 is a front view of the presser member; Fig. 27, 20 a side view of the thread guide drive; Fig. 28, a front view of the thread guide drive; and Fig. 29 is a fragmentary side view partly in section showing the carrier member with its track 14' and a strut with cooperating roller taken on line 29—29 25 of Fig. 9.

Referring to the drawings, the machine frame comprises a plurality of gate-like pedestals interconnected by longitudinal girders and large enough to permit attendants to pass through them. The pillars 1 bear the arch-shaped carriers 2 which support the pedestals 3 for the pairs of discs 4 for suspending two frames. The two discs 4 of a pair are rigidly secured to their supporting shaft 5 which is provided also with the toothed wheel 6 between the discs, the toothed wheel 6 being considerably larger than the discs 4 to obtain greater accuracy in the adjustment of the latter. All toothed wheels engage the pinions 7 which are divided to eliminate play and carried by a continuous shaft 8 positioned in the upper part of the machine frame and serving as changing shaft, the shaft 8 carrying therefor the two adjusting wheels 81 and 82 connected by a decimal gear. The two adjusting wheels 81 and 40 82 are adjusted according to pattern in the usual way by means of an automatic device of suitable type and racks, the ratchet teeth being positioned on the machine frame and actuated in the known manner by the automatic device by means of 45 rods. The transfer of the adjusting wheels 81 and 82 from the domain of the automatic device to that of the embroidering machine represents a considerable step forward especially with respect to accurate adjustment of the frame. The 50 new construction of the frame per se does not require any alteration of the automatic device, and only the adjusting wheels, which are otherwise controlled in the usual way by the gear of the automatic device, are supported by the machine frame instead of by the weak casing of the automatic device. The changing shaft is thus made a part of the embroidering machine so that ratchet teeth engaging the adjusting wheels 81 and 82 during the embroidering operation 55 transmit the reacting forces directly to the firm machine frame and oscillations of the embroidering frame are prevented. The transfer of the adjusting wheels 81 and 82 requires therefore nothing else but an extension of the racks engaging 60 the adjusting wheels so as to make them reach the wheels. The place of installation of the automatic device may be chosen at will, the adjusting wheels being preferably arranged vertically above the automatic device, though a certain latitude 65 70 75 is left in this respect.

The discs 4 are engaged by the carrying bands 9 passing over the idlers 10 which are supported by levers, the adjustment of which permits horizontal straightening of the frame and its carrier members 14 secured to the free depending ends 5 of the bands 9 which, for this purpose, are each provided with a bearing block 12 for a hinge bolt 13. The carrier members 14 suspended from sets of two hinge bolts 13 can be straightened by raising or lowering the idlers 10 so that their upper 10 edges are in alignment. To prevent the bands 9 from slipping off from the idlers 10 during high speed operation, the idlers are provided with guide pins and the bands with perforations adapted to engage the guide pins, or the idlers may be fitted 15 with a lateral flange.

Each carrier member 14 supports by means of a roller 15 a frame strut 16, except the end member which supports a side portion 17 of the frame, the struts 16 and the side portions 17 being bent in 20 opposite directions. The members 16 and 17 are connected at their upper and lower ends by the longitudinal girders, for instance, continuous tubes 18 and 19 which maintain the proper distance between the members and transmit to them 25 the horizontal adjusting motions, which will be explained later on. The side portions 17 of the frame carry also the fabric rollers 20 which are further supported by the struts 16 by means of the curved supports 21. However, while the 30 upper roller is maintained in position merely by a support at the bottom thereof, it is necessary to depart from the usual method relative to the lower roller and to arrange pairs of spoon-shaped or curved supports so as to protect the roller 20 35 against deflections in upward and downward direction, which thus cannot be bent or oscillated either by its weight or the tension of the fabric 22. The supporting devices are the rollers 15 which are mounted on the upper end of the struts 16 and the side portions 17. These supporting 40 devices 15 are supported on the carrier members, that is on the tracks or carrier members 14. The latter are carried by the suspension device, namely, the steel bands 9 and the band discs or idlers 10. 45

The curved supports 21 for the fabric rollers must be vertically and horizontally adjustable to bring the fabric at uniform tension into proper position relative to the embroidering tools.

The frame parts are guided in the known manner by means of the guide rods 23 secured to the frame, and the frame struts 16 are provided with corresponding guide rolls which can be adjusted to set the frame always so that the fabric 22 held between the fabric rollers 20 can be passed 55 freely between the embroidering tools.

To permit lateral adjustment of the frame, the tubes 18 and 19 are either extended over the side parts 17 of the frame and provided on their free ends with the idlers 24 or the latter are secured to special brackets 25 attached to the side parts 17 of the frame, as shown in the drawings. The idlers 24 lean against the vertical adjusting members 26 which are guided horizontally displaceably on the machine frame and provided for this purpose on their upper and lower ends with the rollers 27 which guide the adjusting members 26 along the rails 28 carried by the machine frame.

Furthermore, the upper and lower ends of the adjusting members 26 are engaged by the steel bands 30 guided over the idlers 31 to the discs 32 in such a way that the turning of the latter causes the adjusting members 26 to be displaced parallel to one another and towards one side or the other. Fig. 4 shows that the upper end of the adjusting 70 75 76

member 26 is engaged by only one steel band 30, the lower end, however, by two correspondingly narrower bands symmetrically disposed relative to the upper band to prevent twisting of the frame. The pulleys 32 are each arranged loosely rotatably on a pair of brushes 95 provided on the machine frame and serving as bearing for the main driving shaft 96 of the embroidering machine, each disc 32 being firmly connected with a disc 34. It is important to keep the bands 30 short and the discs 32, 34 near the frame so that longitudinal oscillations or rotations of the bands 30 have no appreciable influence on the adjustment of the frame and the latter can be reliably adjusted without vibration according to the rotation of the discs 32. Far-going elimination of the influence of expansions and vibrations of the machine parts has been aimed at also by suspending the frame by means of the steel bands 9 and 20 by moving the latter by the wheels 6.

The two discs 34 of a frame are interconnected by a steel band 35 in such a way that the band 35 transmits an adjusting motion of one disc to the other. One disc is rotated by the automatic device according to pattern and, according to Fig. 4, connected for this purpose with a gear 90 engaged by a divided pinion 91 adapted to be adjusted to eliminate play. The pinion 91 is disposed on a changing shaft 92 carrying the two wheels 93 and 94 which are rotated in the known manner by the automatic device and connected by a decimal gear.

The steel band 35 is guided over two rolls 36 and 37, the roll 36 being stationary on the machine frame and the other one carried by the lever 39 movably positioned on the shaft 38. The free end of the lever 39 carries the weights 98 by means of the rod 97 to keep the steel band 35 tight. This tension has the additional effect of drawing apart the two adjusting members 26 between which a frame is arranged so that play in the lateral adjustments of the frame is excluded. Instead of tensioning the steel band 35 by the weights 98, a spring of any suitable kind could be used or a part of the steel band could be replaced by a spring. Or the steel band can be dispensed with entirely by causing each of the two discs 34 to be engaged by a weight or a spring so as to draw apart the adjusting members with sufficient force to insure a reliable frame adjustment at high operating speed. Furthermore, instead of transmitting adjusting force from one disc 34 to the other and to include the frame in this transmission system, both discs 34 could be rotated correspondingly by a special continuous adjusting shaft.

The rack mechanism 60 prevents upward motions and thereby oscillations of the lever 39; the mechanism could of course be replaced by an oil damping device, a mechanical braking gear or the like.

The arrangement described can be altered also in other respects and within wide limits, and the drive of the frame in vertical direction can be simplified with particular ease. It is not necessary that each hinge bolt 13 of the carrier members 14 be moved by a separate gear 6. According to Fig. 8, several supporting shafts 5 of the band discs 4 may be combined into a common shaft to turn a common gear 6 so that only a few of such adjusting wheels are required while any number of steel bands in any desired spaced relation to one another may be provided for the carrier members 4. The length of the supporting shafts and the number of band discs 4 secured

thereto should be chosen with a view to excluding completely the formation of vibrations, and the various supporting members should be dimensioned accordingly as to thickness. A further possibility of simplifying the frame drive is shown in Fig. 9 where the carrier members 14 are made so long that they accommodate several frame struts 16, the various path portions 14' being adjustably attached to the carrier members 14 so that the upper edges of the paths can be aligned horizontally. The various members 14 must be dimensioned in this case, too, with a view to preventing excessive sagging and vibrations of the frame resulting therefrom. The length of the path members must be adapted to the changing range of the frame.

The needles 101 are each secured by a clamp screw to individual needle bars 102 in the manner usual in sewing machines, the needle bars being displaceably arranged in the bridge-like bearing bars 104 and 105 of the machine frame. The shuttles operating with the needles are arranged on shuttle carriers or shuttle bars 101'.

In order to couple the needle bars 102 individually with the driving bolt 103, each needle bar is provided with two oppositely disposed and relatively flat notches 106 for the reception of the two rolls 107 which are carried by the levers 108 and are drawn toward one another by means of the small spring 109 so that these coupling members do not exert lateral pressure on the bearings of the needle bars which are thus fully relieved outwardly. Each of the levers 108 is rotatable about a vertical axis and secured to the driving rod 103 which, for this purpose, is provided with the correspondingly distributed ears 300.

A needle bar 102 can be readily separated from the driving rod 103 by pushing apart the two rolls 107. To this end an adjusting slide 111 is positioned above each needle bar on the machine frame and provided at its lower edge with a projecting tongue 112 corresponding in width to the diameter of the needle bar 102. When this tongue 112 is driven between the two rolls 107, according to Fig. 18, they cannot engage the notches 106 of the needle bar and fail to catch the latter. To permit separation of the needle bars 102 from the driving rod 103 only when the former are in returned position, the tongue 112 overlaps in the advanced position shown in Fig. 17 the rear path of the rolls 107 only. If the rolls 107 are within range of the tongue 112, the latter presses them out of the notches 106 so that the rolls 107 can come into contact with the needle bars 102 only during the next advance outside the range of the notches 106, the rolls moving inactively along the needle bars without engaging them. On the return of the tongue 112 the rolls 107 can engage again on their return 60 the notches 106 of the needle bar 102 and carry the latter along. This arrangement affords the advantage that each needle bar, on striking a point in the fabric that is hard to pierce or in case of direct contact between needle and needle plate, automatically disengages itself from the driving device without causing the needle to break and damaging the fabric. To limit the path of the needle bar rearwardly and thus keep the notches 106 within range of the rolls 107, each needle bar is provided with an adjusting ring 113 which butts against the guide bar 105 and the interposed buffer plate 114 consisting of a soft material, such as, for example, rubber or felt. The general arrangement provides that the 75

rolls 107 follow the adjusting ring 113 when pushed apart and, the moment a needle bar is disengaged, press it so closely on to the bar 105 that the locking bolt 115 can engage the notch 117 of the needle bar, the needle bars 102 being secured against rotation during operation by the rolls 107. In a position of rest the bars are secured against rotation by the tongues 112 which engage a clearance of the adjusting ring 113. 10 These means may be replaced or supplemented by others; for example, each needle bar 102 may have a groove 210 and the corresponding guide rail 104 a guide bolt 211.

In order to protect the needle bar 102 after 15 disengagement against being driven by the rolls 107 of the driving rod 103, the bar 105 is provided with a locking bolt 115 for each needle bar, the bolt engaging by means of the spring 116 a small notch 117 of the needle bar as soon as the latter is pushed back, as shown in Fig. 17. The bolt 115 does not interfere in any way with the driving of the needle bars 102 after their attachment to the driving rod 103, since it is pushed laterally out of reach of the needle bar by the 20 rear end of the tongue 112 after the needle bar has become engaged.

Instead of arranging the coupling members connecting the needle bars with their driving rod 3 on both sides of the latter, pawls of the 30 ordinary type could be caused to engage recesses in the needle bars from below. These pawls could be made from laminated springs, one end of which would be secured to the driving rod and the other one bent vertically upwardly. Dis- 35 engagement could then be effected simply by depressing these pawls. Furthermore, instead of employing clamps or pawls for connecting the needle bars 102 with the driving rod 103, spring-actuated and rectilinearly guided carriers, slides, 40 bolts, or other coupling means could be used which would have to cooperate with the adjusting members of the machine frame in such a way that they could be actuated by the latter during operation. For this purpose one of the cooperat- 45 ing members would have to act as running-on bar for the others.

The reciprocating motion of the driving rod 103 can be controlled in various ways from the main shaft 120, the simplest way being to drive 50 it directly by eccentrics positioned on the shaft 120 and balanced by counterweights. The shaft 120 is to be disposed in the needle blocks of the machine in the immediate neighborhood of the driving rod 103 and on a level with the latter, 55 but in the modification shown in the drawings the connecting rod between the eccentrics and the driving rod 103 is provided as short as possible in order to approach as closely as possible the needle bar drive used in sewing machines. 60 To this end the guide shoes 121 by means of which the driving rod 103 is maintained in position relative to the guide rods 122 secured to the machine frame extend up to the eccentrics 123 secured to the main shaft 120. The connecting 65 rod 124 unites the eccentric strap 125 with the guide shoe 121, and in order to guide the bolt 126 exactly on a circle, the following arrangement has been made:

On the main shaft 120 the eccentrics 123 are 70 always disposed in pairs side by side and staggered 90° relative to one another. They drive an auxiliary shaft 127 with two cranks also staggered at 90° relative to one another and connected with the two eccentrics 123 by means of 75 the two rods 128, the crank 127 driving no ma-

chine part but running idle; however, in order to prevent mass actions resulting from its drive to become effective outwardly, it is preferably provided with the eccentric weights 129. Instead of using the auxiliary crank 127, one could provide any suitable type of guide for the guide rod 128 attached to the eccentric strap 125, or the connecting rod 124 could be rigidly united with the eccentric strap 125 or cranks could be employed instead. On account of the elimination 10 of the intermediate gears, especially of the oscillating shafts, usually employed for driving the driving rods for the needles, great working speed and vibrationless running of the machine are attained. For the same reason the driving rod 15 103 is composed of a plurality of relatively short, thin and light parts, and, at each point of separation, a guide shoe provided each of which is fitted with eccentric drive.

The slide 111 preferably made from sheet metal 20 and connected at its front end with the tongue 112 extends vertically and possesses at its rearward end a handle 118 by means of which it can be adjusted by hand during operation of the machine. At its lower edge two notches 119 are 25 provided for locking it in any desired position by means of the pin 170 attached to a shield 171 which is positioned on an adjusting shaft 172 adapted to be moved by hand or by the automatic device through the medium of the bar 173 30 and the lever 174 secured to the shaft 172, so that all slides 111 can be moved forward and backward simultaneously and all needle bars 102 simultaneously connected with, or disconnected from, the driving rod 103, the work of the machine being temporarily interrupted in the latter case without stopping the machine drive. Instead of one adjusting shaft 172 a plurality of them may be provided for uniformly engaging and disengaging groups of needles in a certain 40 order, an arrangement which, for example, would be important relative to the change of repeat and the general carrying out of fancy embroidery work. Each slide 111 has also a recess 175 through which passes a second pin 176 on the 45 shield 171, which serves the purpose of keeping the slide 111 within range of the pin 170. It is essential that during the manual or automatic engagement or disengagement of the needle bars the particular manually made adjustment of the 50 slides 111 remain unaltered, as the latter are held by springs in their special position relative to the shield 171.

In the manufacture of high speed embroidering machines special attention must be paid to 55 the bore tool drive, in addition to the needle drive, as cam drive should be avoided. What has been said about the needle drive, applies, therefore, in the main to the bore tool drive also, while it should be observed that the bore tools 60 are to be positioned not below the needles, as is usual, but between them in order to make the employment of circular shuttles possible.

The bore tool rod 130 is subdivided many times like the needle driving rod and, according to 65 Figs. 19 and 20, displaceably arranged with its shoe 131 on the guide rods 122. Each guide shoe 131 is engaged by means of the bolt 132 by a toggle drive 133, 134, and the toggle arm 134 secured to an eccentric strap 135 surrounding 70 the eccentric 136 connected with the main shaft 120.

The hinge bolt 137 of the toggle 133, 134 carries on each of its ends a block 138 guided in one or the other of the two links or cam portions 139 75

firmly connected with one another by the bow or frame 140 and movably supported on the machine frame by means of the pins 141. The links 139 are shaped so that they form an arc around the hinge pin 132 of the toggle portion 133 in the position shown in Fig. 19 and during the rotation of the eccentric 136 the hinge pin 137 of the toggle 133, 134 is reciprocated on an arc portion about the pin 132 without, however, transmitting any motion to the latter and thus to the bore tool rod 130. In this way, all driving parts of the bore tool rod with the exception of the bore tool rods themselves are moved continually, whereby the bore device is prevented from sticking after having not been used for some time and from being broken as a result thereof on being started again. The wear is very slight, as the driving parts are relieved. On the other hand, if the cam portions 139, 140 are moved into the bore position shown in Fig. 20, the pin 137 is, during the rotation of the eccentric 136, guided so that a corresponding sliding motion of the bore tool driving rod results therefrom without requiring a special control step as in the known types of embroidering machines. The displacement of the cam portions 139 takes preferably place when the pin 137 is approximately or exactly positioned in the axial direction of the pins 141 so that the change can be effected with little resistance.

The adjustment of the bore tools as to depth is made by means of a cam 142 engaged by a guide pin 143 on the cam portion 139. These cams 142 are formed so as to permit rapid advance of the bore tools towards the fabric by means of only four steps so that eight of the usual twelve steps can be applied to the regulation of the depth of penetration. All cams 142 arranged along the embroidering machine for the purpose of regulating the depth of penetration of the bore tools are disposed on an adjusting shaft 144 which runs parallel to the shaft 120 and uniformly moves all bore tool driving devices. The shaft 144 is displaced in the known manner by an automatic device.

The presser members 150 for the fabric are secured in the usual way to the bar 151 screwed to the bosses of the levers 153, any number of which may be carried by the shaft 152 rotatably arranged on the needle block. The levers 153 are engaged by the springs 530 tending to press the members 150 on to the fabric 160. The free end of each lever 153 is connected by the bolt 531 with a double-armed auxiliary lever 532, one arm 55 of which carries the regulatable setting screw 533 adapted to hug a lateral projection of the lever 153, while the other arm of the lever 532 carries the roll 156 which is kept in permanent contact with the cam 154 by the action of the spring 155 which engages the lever 532, the cam 154 being firmly located on the main shaft 120.

According to Fig. 23, the lever 532 when in a position of rest is depressed by the cam 154 to such an extent that the screw 533 hugs the lever 153 and depresses it so that the presser members 150 are lifted off from the fabric 160. During the rotation of the shaft 120 the lever 532 is raised at first only far enough to cause the presser members 150 to come in contact with the fabric 160 and to remain for a moment in a position of rest. The cam 154 contains therefore a short concentric arc portion between the cam portions 157 and 158 which move up the lever 532. By means of the cam portion 158 the lever 532 is finally adjusted so that the set screw 533 is out

of contact with the lever 153 which is thus exposed to the action of the spring 530 which presses the members 150 against the fabric 160 and thus the latter on to the needle plates 161. Owing to the intermittent motion of the presser members 150, the otherwise unavoidable impact on striking the fabric is completely eliminated. Furthermore, the lever system described insures also constant good contact between the roll 156 and the cam 154.

According to Figs. 27 and 28, the thread guides 163 are secured to the bar 164 carried by the levers 165 which are connected with the shaft 166 carrying also the driving levers 167. Each of these is engaged by a rod 168, the free ends of which are provided with the bolts 169 engaging with one end the cam 200 on the main shaft 120 and with the other, the link 201. At the rotation of the cam 200 the pin 202 is thus moved up and down in the link 201 which can be moved at its top about the pin 202 arranged on the machine frame. The bolt 203 provided at its lower end is engaged by the adjusting rod 204, the other end of which is disposed on, and guided by, the shaft 144 serving for adjusting the bore tool drive, and adjusted by a cam 205 arranged thereon so that the engagement and disengagement of the bore tool drive is followed by a corresponding adjustment of the thread guide drive, the shaft 144 being controlled by the automatic device.

The link 201 is shaped like an arc, the radius of which corresponds to the rod 168. When brought into the position shown in Fig. 27 where it forms an arc about the lower end of the lever 167, no motion is transmitted to the thread guides 163 during the ascent and descent of the pin 169. On the other hand, if the link 201 is obliquely adjusted by the turning of the shaft 144 and the cam 205, the motion of the pin 169 along the link 201 will bring about a motion of the thread guides 163, the extent of the said motion depending on the adjustment of the cam 205. The adjustment of the link 201 is preferably effected when the pin 169 is exactly or approximately positioned in the axial direction of the bolt 202 of the link in order to keep the adjusting resistance down to a minimum.

I claim:

1. In an embroidering machine the combination of a reciprocating rod with needles, a carrier bar with shuttles cooperating with the needles, fabric rollers, a frame for fixing therein the fabric to be embroidered and consisting of longitudinal girders, side portions and struts connecting the said longitudinal girders and serving as bearing for the fabric rollers, supporting devices on the said frame struts and side portions, carrier members adapted to support the said struts and side portions of the said frame, a suspension device carrying the said carrier members and adapted to bear the weight of the said frame, and an automatic device adapted to adjust the said suspension device.

2. In an embroidering machine the combination of a reciprocating rod with needles, with a carrier bar with shuttles cooperating with the needles, fabric rollers, a frame for fixing therein the fabric to be embroidered, the said frame consisting of longitudinal girders, side portions and struts connecting the said longitudinal girders and serving as bearing for the fabric rollers, supporting devices on the said frame struts and side portions, articulated carrier members adapted to support the said struts and side portions of the

said frame, a suspension device carrying the said articulated carrier members at their joints and adapted to bear the weight of the said frame, and an automatic device adapted to adjust the said suspension device.

5. In an embroidering machine the combination of a reciprocating rod with needles, with a carrier bar with shuttles cooperating with the needles, fabric rollers, a frame for fixing therein the fabric to be embroidered and consisting of longitudinal girders, side portions and struts connecting the said longitudinal girders and serving as bearing for the fabric rollers, supporting devices on the said frame struts and side portions, articulated carrier members adapted to support the said struts and side portions of the said frame, steel bands carrying the said articulated carrier members at their joints, adjusting discs to which the free ends of the said steel bands are connected, a plurality of supporting shafts coaxially arranged on the machine and adapted to carry the said adjusting discs, driving wheels carried by the said shafts, a shaft passing through the entire embroidering machine, small toothed wheels disposed on the said shaft and adapted to rotate the said driving wheels, and an automatic device adapted to adjust the said continuous shaft.

4. In an embroidering machine the combination of a reciprocating rod with needles, with a carrier bar with shuttles cooperating with the needles, fabric rollers, a frame for fixing therein the fabric to be embroidered and consisting of longitudinal girders, side portions and struts connecting the said longitudinal girders and serving as bearing for the fabric rollers, supporting devices on the said frame struts and side portions, carrier members adapted to support the said struts and side portions of the said frame, a plurality of members connected with each carrier member and adapted to be adjusted relative to one another, a suspension device carrying the said carrier members and adapted to bear the weight of the said frame, and an automatic device adapted to adjust the said suspension device.

5. In an embroidering machine the combination of two oppositely disposed rods with needles adapted to be reciprocated in opposite direction to one another, two bars with shuttles arranged between the said needle rods and adapted to operate with the needles, fabric rollers, a frame at each needle rod for fixing therein the fabric to be embroidered and consisting of longitudinal girders, side portions and struts connecting the said longitudinal girders and serving as bearing for the fabric rollers, supporting devices on the said frame struts and side portions, carrier members adapted to support the said struts and side portions of the said frame, a suspension device carrying the said carrier members and adapted to bear the weight of the said frame, and an automatic device adapted to adjust the said suspension device, the said frames being suspended at the two needle rows to balance each other and to move oppositely to each other in vertical direction and in the same way in horizontal direction.

6. In an embroidering machine the combination of a reciprocating rod with needles, a carrier bar with shuttles cooperating with the needles, fabric rollers, a frame for fixing therein the fabric to be embroidered and consisting of longitudinal girders, side portions and struts connecting the said longitudinal girders and serv-

ing as bearing for the fabric rollers, spoon-shaped means adapted to hold the lower fabric roller upwardly and downwardly relative to the frame, supporting devices on the said frame struts and side portions, carrier members adapted to support the said struts and side portions of the said frame, a suspension device carrying the said carrier members and adapted to bear the weight of the said frame, and an automatic device adapted to adjust the said suspension device.

7. In an embroidering machine the combination of a reciprocating rod with needles, a carrier bar with shuttles cooperating with the needles, fabric rollers, a frame for fixing therein the fabric to be embroidered and consisting of longitudinal girders, side portions and struts connecting the said longitudinal girders and serving as bearing for the fabric rollers, guiding means on the side portions of the said frame, adjusting means adapted to guide the side portions of the said frame in vertical direction, guiding means on the machine frame adapted to horizontally guide the said adjusting means, drawing devices adapted to engage the upper and lower end of the said adjusting means to draw them apart, supporting devices on the said frame struts and side portions, carrier members adapted to support the said struts and side portions of the said frame, a suspension device carrying the said carrier members and adapted to bear the weight of the said frame, and an automatic device adapted to adjust the said suspension device.

8. In an embroidering machine the combination of a reciprocating rod with needles, a carrier bar with shuttles cooperating with the needles, fabric rollers, a frame for fixing therein the fabric to be embroidered and consisting of longitudinal girders, side portions and struts connecting the said longitudinal girders and serving as bearing for the fabric rollers, guiding means on the side portions of the said frame, adjusting means adapted to guide the side portions of the said frame in vertical direction, guiding means on the machine frame adapted to horizontally guide the said adjusting means, drawing devices adapted to engage the upper and lower end of the said adjusting means to draw them apart, steel bands making up the said drawing devices, adjusting discs connected with the free ends of the said steel bands, the said adjusting discs being interconnected by steel bands, and an automatic device adapted to rotate the said adjusting discs.

9. In an embroidering machine the combination of a reciprocating rod with needles, with a carrier bar with shuttles cooperating with the needles, fabric rollers, a frame for fixing therein the fabric to be embroidered and consisting of longitudinal girders, side portions and struts connecting the said longitudinal girders and serving as bearing for the fabric rollers, supporting devices on the said frame struts and side portions, articulated carrier members adapted to support the said struts and side portions of the said frame, steel bands carrying the said articulated carrier members at their joints, adjusting discs to which the free ends of the said steel bands are connected, a plurality of supporting shafts coaxially arranged on the machine and adapted to carry the said adjusting discs, driving wheels carried by the said shafts, a shaft passing through the entire embroidering machine, small toothed wheels disposed on the said shaft and adapted to rotate the said driving wheels, a differential gear arranged on the continuous shaft supported on the machine frame, driving means for moving the

wheels of the differential gear, and an automatic device adapted to adjust the said driving means.

10. In an embroidering machine the combination of a reciprocating rod with needles, a carrier bar with shuttles cooperating with the needles, fabric rollers, a frame for fixing therein the fabric to be embroidered and consisting of longitudinal girders, side portions and struts connecting the

said longitudinal girders and serving as bearing for the fabric rollers, carrier members adapted to support the said struts and side portions of the said frame, a suspension device carrying the said carrier members and adapted to bear the weight of the said frame, and an automatic device adapted to adjust the said suspension device.

MAX BRETSCHNEIDER.
